LIFT FORK FOR STACKING ARTICLES

Everett Hall and James H. Walsh, Bridgeton, N.J., assignors to Owens-Illinois Glass Company, a corporation of Ohio

Filed Apr. 11, 1958, Ser. No. 727,909

4 Claims. (Cl. 214—653)

The present invention relates to lift forks used for lifting and transporting loads of articles, each load consisting of a multiplicity of articles such as filled cartons or boxes, stacked or arranged in a compact pile or group, and more particularly to improvements on a lift fork of the general type shown and described in Patent No. 2,530,375, issued to V. H. Cartwright. In this patent there is disclosed a lift fork comprising a pair of vertical parallel relatively movable frames, one of which is constructed to be attached to a lift fork truck or vehicle equipped with means for raising and lowering the frame, and the other of which carries horizontally extending tines adapted to engage the load. These tines are equipped with laterally operable and opposed gripper devices which are expansible or retractable to grip articles at the lower courses of the load and lift them together with the remaining upper portion of the load. The upper portion of the load is supported by the top surface of these tines, principally, and to some extent may receive some support from the gripped articles in the lower courses of the load.

The present invention, in the preferred form herein illustrated, provides an efficient means for expanding and contracting the gripper means under the positive control of the lift fork operator so that the articles in the lower portion of the load, when lying between the tines of the fork, may be gripped for lifting independently of action of the lift fork on the upper portion of the load, this being one of the objects attained by the invention.

Another object of the invention is to provide a lift fork apparatus which will handle from one article to a full load of articles, thereby eliminating the prior practice of handling partial loads manually.

Another object of the invention is to provide independently controlled fluid actuated means for expanding and contracting the gripper devices carried by the tines, their gripping force being regulable, when gripping articles to lift them, not to exceed a gripping force that will cause damage to the articles.

Another object of the invention is to provide a lift fork apparatus having the foregoing advantages that is easily and economically constructed and maintained.

Another object of the invention is to provide individual fluid-actuated motors that are remotely controlled for operation in unison for expanding and contracting the gripper devices on each of the tines for, at will, gripping and releasing articles put between the tines.

Other objects and advantages of the present invention will become apparent from a reading of the following description of a preferred embodiment, the appended claims, and the accompanying drawings of the preferred embodiment to which reference is made and in which:

Fig. 1 is a three-quarter front perspective view of the lift fork of the apparatus, a portion of a lift truck or vehicle appearing in phantom view.

Fig. 2 is a rear elevational view of the lift fork frame taken along line 2—2 of Fig. 1.

Fig. 3 is a partially diagrammatic view, showing the fluid system and controls for actuation of the fluid operating motors drivably connected to expand or contract one of the gripper devices.

5 Fig. 4 is a sectional view of the control valve of the system for manually controlling operation of the motors.

Referring to Fig. 1, which illustrates the lift fork apparatus, the apparatus includes a supporting frame 10 which is movably attached to a lifting frame 11 mounted at the front of a truck or vehicle 12, said lifting frame being power operated for lifting and lowering the fork. The supporting frame 10 has a vertical wall frame 13 attached thereto and in spaced relationship. The vertical wall frame 13 has a plurality of tines 14 depending horizontally from the lower portion 13a of the wall frame. The tines 14 extend horizontally forward and are spaced apart in parallel relationship, one to the other, the spacings therebetween being substantially equal. Any desired number including at least two tines 14 may be built into the structure. The outermost or end tines 14 are provided with a single set of gripper bars 15, on their inside vertical faces and the intermediate tines between the end tines are provided with two sets of gripper bars 15 on both inside vertical faces. The gripper bars 15 are arranged to oppose complementary gripper bars on the adjacent tine 14 and are movable laterally with respect to the tines by expanding and retracting movement to engage an article placed between the tines. The gripper bars 15 are mounted for movement similar to that disclosed in the Cartwright patent, No. 2,530,375, and are actuated in expanding and retracting movement by reciprocating movement of longitudinal linkage members 16 (Fig. 3) slidable within each tine 14.

As seen in Fig. 3, each of the longitudinal members 16 is pin connected to a pivotal crank 17 by pin 18, the crank 17 being pivoted on a bracket 19 integral at the back side of the lower portion 13a of the wall frame 13. This crank connection is provided for reciprocal action of each longitudinal member 16 in tines 14.

40 Fluid-operated motors 21 are provided to drive each member 16, the motors being in the form of cylinder-piston assemblies, which comprise a cylinder 22 with opposite end ports 23 and 24 for the admission of pressure fluid to move its internal piston in either direction. The piston (not shown) carries a connecting rod 25 having an end block 26 and is pivotally connected thereby at its outer end to the free end of the corresponding crank 17 by a pin 27 extending through one of the series of holes 28 in block 26. This series of holes 28 permits a

50 stroke adjustment for each of the motors 21. As indicated on Fig. 2, the outermost motors may be of smaller size than the motors located inwardly therefrom, since these outermost motors are required to drive but one set of the gripper bars 15 at the innerfacing on each of the outermost or end tines. The tines located intermediate these two end tines each have a double set of gripper bars facing in opposite directions on their vertical facings, hence, the motor for driving them is preferably of a correspondingly larger size. In any event, each of the motors 21 are mounted similarly and operate in the same manner and in unison, as will be presently described. Each cylinder 22 of the two outermost motors have an upper end lug 29 pin connected at pin 30 to bracket 31

60 projecting rearwardly on lower wall frame 13a. The centrally disposed motor 21 has a similar pin connection on crossbar 32 across the uprights of wall frame 13. Thus, the cylinders of the motors 21 are each held on the wall frame of the lift fork.

65 As seen from Figs. 2 and 3, each of the motors are connected into a pressure fluid system for activating the motors in either direction. In this connection, the sys-

tem herein illustrated is provided for operating double-acting cylinder assemblies, however, it should be obvious that single-acting cylinder piston assemblies would operate just as well if, as will be seen from the following description of the system for double-acting cylinders, the movement of the motor for releasing the gripper devices is powered by a spring biasing the power or positive stroke of the cylinder.

From Fig. 3, we see that a sump and pump unit 33 supplies a continuous source of fluid under pressure into a conduit 34. Conduit 34 is connected in series with a conventional variable pressure regulator 35 that is adjustable for regulating the pressure of the fluid being supplied from the pump. At the outlet side of the pressure regulator is a conduit connection 36 to the inlet port 37 of a manually-operated control valve, referred to generally as 38. A pressure gauge 39 may be interposed in conduit 36 to indicate a measurement of the pressure of the fluid that is being supplied by the pump through the pressure regulator 35. As may be seen from Fig. 4, with occasional cross-reference to Fig. 3, the control valve 38 has an axial shiftable valve spool 40 having three annular lands 41, 42, and 43 thereon. The central shaft 44 of the valve spool 40 extends outwardly of the body of the valve 38 and is sealed against leakage by a gland 45. The outer end of shaft 44 has a pivotal connection to the lower end of control lever 46 at a yoke 47 pinned through a bearing 44a on shaft 44. The lever 46 is mounted on a pivot 48 journaled on a bracket 49 which is part of the vehicle 12. Lever 46 is shiftable between the extreme settings A (solid outline) and B (dotted outline) and is capable of being set in an intermediate position C. The pump and sump unit 33 is preferably mounted on the truck 12 of the lift fork apparatus and driven by power take-off connection (not shown) from the vehicle 12. The control valve 38 and lever 46 may be conveniently mounted on the vehicle 12 for ready access to these controls by the lift fork operator.

The control valve 38 has ports 50 and 51 connected by fluid conduits 52 and 53, respectively, which extend to respective connections on a first header 54 and a second header 55. These first and second headers 54 and 55 are fastened transversely of the vertical uprights at the back of the wall frame 13. The first header 54 has fluid connections by conduits 56 to the upper port 23 of each of the cylinders 22 of the motors. The second header 55 has fluid connections by conduits 57 to the lower port 24 of each cylinder 22 of the motors. The valve 38 also has upper exhaust ports 58 and 59 connected, respectively, by fluid connections at conduits 60 and 61 leading to the sump of the pump-sump unit 33.

Hence, as the control lever 46 is set in the position A (shown in solid outline), fluid from the pump enters the valve 38 at port 37 and is conducted between lands 42 and 43 of the valve spool 40 to the port 51 and into the first header 54 through conduit 53. The pressure fluid present in the first header is then conducted through the three conduits 56 into the upper ports 23 of the three cylinders 22 of the motors forcing their pistons downwardly to extend the connecting rod 25. Fluid below the pistons is permitted to exhaust out ports 24, conduits 57 and flow to second header 55, thence through conduit 52, valve port 50, exhaust port 58, conduit 60, and to the sump of pump-sump unit 33. This permits driving motion by the motors to rotate the three cranks 17 counterclockwise about their pivots 20 to drive the longitudinal linkage members 16 longitudinally into the tires and force the gripper bars 15 to expand against an article placed between the tires. By setting the pressure regulator 35 of this system to a fluid pressure corresponding to a driving force of the motor that is slightly in excess of the force necessary to grip and lift articles engaged by the gripper bars will provide a satisfactory means for handling these articles without causing damage thereto by excessive compressive forces upon gripping them. The control

lever 46 may also be set in its intermediate position C in which event the valve spool lands 41, 42, and 43, respectively, will block ports 58, 37, and 59 of the valve and lock the gripper bars on the tires in gripping engagement on the articles.

To release gripped articles, the control lever may be shifted to the indicated position B, in which event the valve spool 40 will connect fluid pressure entering at inlet port 37 to port 50 and conduct fluid pressure through conduit 52 to the second header 55. The pressure then in header 55 will be distributed through conduits 57 to enter the cylinders 22 of the three motors through their lower ports 24 and actuate their pistons upwardly. Fluid above the pistons of cylinders 22 is exhausted through ports 23, conduits 56, first header 54, conduit 53, port 51, exhaust port 59, and conduit 61 to the sump. This movement will drive the crank 17 in a clockwise direction about their pins 20 and withdraw the longitudinal linkage member 16 in the tires 14 causing the gripper bars 15 to retract and release the articles.

Various modifications may be resorted to within the spirit and scope of the appended claims.

We claim:

1. In a lift fork apparatus for carrying articles provided with a frame adapted to be mounted for vertical movement on a vehicle and including a plurality of parallel members attached to depend horizontally from said frame and having equal spacing therebetween to receive articles, and opposed article gripper means movable on said members in cooperating relationship to act on articles received between said members when moved in one direction and to release the articles when moved in the other direction, in combination therewith, a longitudinally disposed linkage along each said member and operable by reciprocating movement to move said gripper means in either direction, a crank arm operatively connected to each said linkage and pivotally mounted on the frame, fluid-operated reciprocating motors for driving said linkages individually through pivotal connection of the connecting rod thereof on said crank arm, the cylinder of said motor being held on the frame, opposite end ports in the cylinder of each said motor, a first fluid header, fluid conduits connecting said first header to one end port of each said cylinder, a second fluid header, fluid conduits connecting said second header to the other end port of each said cylinder, a fluid pressure source, a sump, a hand-operated control valve, fluid conduits connecting the control valve respectively to the source, first header, second header and the sump, said control valve being adapted for settings alternatively to: (1) connect the first header and the source and the second header and the sump and cause pressure fluid to actuate each of the motors to move their said linkage and gripper means in the direction to act on articles between said members, and (2) connect the second header and the source and the first header and the sump and cause pressure fluid to actuate each of the motors to move their linkage and gripper means in the direction to release said article.

2. The combination defined in claim 1, wherein the said control valve includes an alternative hold setting, said setting blocking the respective connections between both said first and second headers and the pump and the sump, whereby the motors lock the article gripping means against movement in either direction.

3. The combination defined in claim 1, characterized by including a variable pressure regulating means in the fluid conduit between the first header and the source, thereby to permit regulation of the pressure actuating force of the motors in moving the gripper means in the direction to act on a given kind of articles of slightly more than the gripping force necessary to lift one of said articles and prevent damage thereto upon gripping same.

4. The combination defined in claim 3, including, in operative series connection in said fluid conduit with the

5

variable pressure regulating means, a pressure gauge indicating the amount of fluid pressure being delivered to said first header.
